UNITED STATES PATENT OFFICE.

ALFRED HENRY STOCKALL, OF BATH, ENGLAND.

PRINTER'S GALLEY.

Application filed July 9, 1923. Serial No. 650,401.

To all whom it may concern:

Be it known that I, ALFRED HENRY STOCKALL, a British subject, and a resident of Bath, in the county of Somerset, England, have invented certain new and useful Improvements in Printers' Galleys; and I do hereby declare the following to be a full, clear, and exact description of the same, reference being had to the accompanying drawings, forming part of the specification, and to the characters of reference marked thereon.

This invention relates to printers' galleys and refers chiefly to galleys which are adapted for use on type casting and composing machines wherein the lines of single types as cast by the machine are assembled in a column in the galley in the reverse order to composition so that the last line 20 to be thus assembled is the first line of the composed matter. A casting and composing machine of this class is described in the specification of United States Patent 625,998.

25 In order to avoid the necessity of transferring the lines of type bodily from this galley to another to facilitate "making up" and so as to place the first line of composition at the head of the galley, it has been proposed to provide for the open or receiving end of the galley a movable or detachable end member or bar which can be placed in position to close the end of the galley and permit the lines of type to be 35 moved towards this bar with the first line of composition nearest the now closed end of the galley.

Where, hitherto, detachable ends have been employed these have necessitated comparatively elaborate securing devices, devices which have not been satisfactory, or devices which have not been easily manipulated. Where movable ends have been employed, they have necessitated considerable 45 departures from the usual structural form of galley and have been in the way when not acting to close the end of the galley.

It is the chief object of the present invention to provide a removable end for such 50 galley and a securing device which is operated by the user in the act of inserting or removing the end member, and which will act to close the end member in position without necessitating a separate or special 55 act of the user for this purpose.

According to the present invention the

end piece or bar is slightly shorter than the width of the galley and is furnished with projecting ends which pass into or through holes in the side walls of the galley and the 60 catch or securing member comprises or consists of a flat spring secured to the outside of one of the side walls of the galley and adapted to press against one of the projections on the end bar.

65 To place and secure the end bar in position the projection on one end thereof is pushed through the hole in the corresponding side wall and deflects or bends the spring. The end bar is then dropped into 70 position to allow the projection on the other end to enter the hole in the other wall. On the user releasing his hold from the end bar the spring will move the bar lengthwise until the opposite end thereof is pushed 75 against the opposite galley wall. In this final position the spring will still be deflected or bent slightly and will thus hold and lock the end bar firmly in position.

80 Referring to the accompanying drawings:—

Fig. 1. is a plan of the end portions of a galley embodying the present invention.

Fig. 2. is an end section showing the detachable end bar in position and 85

Fig. 3. is an end elevation showing the end bar in an intermediate position.

A is the galley. B the detachable end bar and C is the securing spring.

90 The side walls A' of the galley A are conveniently of L shape and are secured to the floor of the galley by rivets or in other appropriate manner (see Figs. 2 and 3).

The detachable end bar B is also conveniently of L shape so that when in position it rests firmly on the floor of the galley. 95

On one end of the bar B is a projection B' which is adapted to enter a hole A² in one of the side walls A'. On the other end of the bar B is a projection B² which is somewhat longer than the projection B' and is adapted to pass through an opening A³ in the opposite side wall A'. 100

The securing member or spring is in the form of a flat spring C which is disposed 105 on the outside of one of the side walls so that its free end passes or extends over the opening A³ (see Fig. 1).

The end bar B is placed in position by first inserting the projection B' thereon into 110 the opening A³ in the side wall and moving the member B to the right as shown in Fig.

3 until the projection B' can drop inside the wall B' when the projection B' will be in line with the hole A². In doing this the 5 spring C has been engaged by the projection B² and deflected or bent as shown in Fig. 3. When the user releases his grip from the bar B the spring C will move the bar endwise until the left hand end of the member B is against the wall A' in which 10 position the projection B' is pushed into the hole A² and the spring C has been allowed to return to a position almost flush with the wall of the galley (see Figs. 1 and 2). Sufficient power being left in the spring to clamp 15 the bar or lock it firmly in position and against accidental displacement.

Thus the locking and securing of the bar B does not call for any special act on the part of the user as the spring C is first deflected by the act of inserting the bar B and the spring is self-acting to secure or lock the bar in position.

What I claim is:—

1. In a printer's galley, the combination 25 with the upstanding side walls of a removable end bar engaging the side walls and locking means for said end bar, operable

by said end bar to permit the withdrawal and positioning of the bar.

2. In a printer's galley, the combination 30 with a removable end bar, of a spring carried by the side wall of the galley adapted to be deflected by the end bar to permit the positioning of the bar, and thereafter to press on one end of the bar and lock it when 35 in position.

3. In a printer's galley, the combination 40 with a removable end bar of a self-acting spring carried by the galley wall for securing the bar in position.

4. In a printer's galley the combination 45 with an end bar of a short projection on one end thereof adapted to enter a recess in one of the side walls, a long projection on the other end of the bar adapted to press through a hole in the other side wall and a spring secured to the outside of the galley so as to be engaged by the long projection on the end of the bar.

5. In a printer's galley, the combination 50 with a detachable end bar of self-acting means for engaging one end of the end bar to lock it in position.

ALFRED HENRY STOCKALL.
